INVENTOR

JOSEPH KOZIAŁEK

BY *P. J. M.*

ATTORNEY

UNITED STATES PATENT OFFICE.

JOSEPH KOZIATEK, OF NEW KENSINGTON, PENNSYLVANIA.

TOY.

1,313,994.

Specification of Letters Patent. Patented Aug. 26, 1919.

Application filed March 13, 1919. Serial No. 282,336.

To all whom it may concern:

Be it known that I, JOSEPH KOZIATEK, a citizen of Poland, residing at New Kensington, county of Westmoreland, and State of

5 Pennsylvania, have invented certain new and useful Improvements in Toys, of which the following is a specification.

This invention relates to improvements in toys for amusing children, and has as its 10 special purpose the provision of a toy in which certain objects simulative of human beings are caused to move upon a platform, in the manner of waltzing, other objects waving a flag at intervals, while still another object mounted upon a representation of a horse is caused to move in the manner of a rider, all of the several objects being operable by drawing the wheeled platform over a level surface.

20 This purpose is attained by the novel construction and combination of parts herein-after described and shown in the accompanying drawings, forming a material part of this disclosure, and in which:—

25 Figure 1 is a perspective view showing a toy made in accordance with the invention.

Fig. 2 is a bottom plan view of the same, and

30 Fig. 3 is a longitudinal sectional view taken substantially through the center of a platform.

Referring to the drawings, a platform 10, substantially rectangular in profile has an 35 extending front portion 11, terminating in angular elements 12, provided with openings 13 in which may be engaged cords or other means for hauling the device. This platform has attached to it downwardly extending bracket elements 14 and 15, respectively at the rear and narrow portion 12 in which are journaled shafts 15' and 16, mounted upon wheels 17, preferably having a rubber tire so as to avoid damage to 40 the objects which may come in contact therewith.

A wheel 18, mounted on a bracket 19 extending from one of the sides of the platform, is adapted to make contact with the 45 surface over which the other wheels are passing, this wheel being secured upon a spindle 20, having a support 21, formed with a bracket 22, arranged below the platform 10.

50 Also mounted upon the spindle 20 is a pinion 24 its teeth engaging in downwardly

extending peripheral teeth 25, formed with a disk 26 positioned in an opening 27, in the platform 10 near its center, and pivoted on a central stem 23.

60

Standing upon the upper surface of the disk 26 are a pair of objects representing male and female figures 28 and 29, the same being in the position of a waltz, and when the wheel 18 makes contact with the surface, the disk is caused to rotate together with the figures thereon.

65

A rear figure 30 is fixed upon the platform 10, in position and is provided with an arm 31 pivoted at the shoulders 32, the 70 hand 33 grasping a flag staff 34, attached to the flag 35, while upon a projection opposite the fulcrum point of the arm is attached a cord 37, passing downward through a clip bracket 38, formed by a raised portion of 75 the platform 10.

The cord passing through the bracket is attached to the free end of a spring strip 40, pivoted on a projection 41 at one end, while its free end is contactable with a pin 80 42 set in the upper surface of the rotating disk 26, so that when the latter revolves, as to swing the arm laterally outward, causing pulling on the cord 37 and raising the arm carrying the flag, and when the pin has 85 passed the spring strip 40, the arm and flag are returned to normal position, due to their weight.

Near the front of the platform and upon its upper surface, is attached a raised wire 90 rod 44 and engaged therewith are the rear limbs 45 of an object representing a horse 46, carrying a rider 47, bearing a staff of any preferred emblem and simulating a soldier. One of the front legs 48 of the object 95 simulating an animal, is engaged with a crank 50, formed with a shaft 16, so that as the front wheels are rotated the horse is caused to raise and lower in the manner simulative of a galloping horse, the crank 100 being connected by a link to the animal's forelegs for that purpose.

From the foregoing it will be seen that a toy has been disclosed which, by the attitudes and movements of the several figures 105 engaged therewith, excites pleasurable amusement in children for whom the toy is designed.

It will furthermore be seen that the toy is of a lasting character, and when properly 110 and reasonably used, is capable of long and extended use.

Having thus described my invention and set forth the manner of its construction and use what I claim as new and desire to secure by Letters Patent, is:—

- 5 1. In a toy, the combination with a platform having a pair of wheels at the front and rear respectively, a fifth wheel mounted on a transverse axis below said platform, a disk rotatable on a vertical axis, means for actuating said disk by said fifth wheel, a projection on the surface of said disk, an object on said platform having a pivoted arm, a spring strip secured at one end on said platform its free end being contactable 10 with said projection, and flexible connections between the free end of said strip and the arm of said object whereby it is caused to rise and fall when said disk makes one complete revolution.
- 15 2. In a toy, the combination with a platform having a pair of wheels at the front and rear thereof, a figure simulative of a galloping horse hingedly mounted on said

platform at the rear legs, a crank axle between the wheels at the front of said platform, said crank engaging the front legs of the horse whereby it is caused to rise and lower as said platform is advanced, a figure at the rear of said platform, an arm pivoted on said figure, a spring strip engaged at one end on said platform, a clip bracket fixed on said platform, a flexible cord connecting between the free end of said strip and said arm at a point rearward of its axis and passing through said bracket whereby when said spring strip is flexed said arm is permitted to swing down, a disk rotatable on said platform, means for actuating said disk and means for flexing said spring strip carried by said disk, said spring strip normally holding said arm in a raised position.

In testimony whereof I have affixed my signature.

JOSEPH KOZIATEK.
